UNITED STATES PATENT OFFICE.

JAMES M. COUGHLIN, OF KINGSTON, PENNSYLVANIA.

SHIPPING CAN.

Application filed February 24, 1925. Serial No. 11,245.

To all whom it may concern:

Be it known that I, JAMES M. COUGHLIN, a citizen of the United States, residing at 19 N. Dorrance St., Kingston, in the county of Luzerne and State of Pennsylvania, have invented a new and useful Shipping Can, of which the following is a specification.

This invention relates to shipping containers of the metal drum type and more particularly to a closure for use in connection therewith, one of the objects being to provide a closure which acts as a positive seal so as to prevent powdered contents of the container from sifting therefrom.

Another object is to provide a closure which, when subjected to the weight of the contents of the container, will not work loose but, on the contrary, will act to more tightly seal the container.

A still further object is to provide a closure which can be applied readily and will maintain the container sealed in spite of any rough usage to which it may be subjected.

It is the practice to ship poisons in powdered form in metal drums but great care must be exercised to prevent any of the powder from sifting out of the containers. Otherwise poison lost in this way is likely to be left in cars subsequently used for transporting stock food with the resultant loss of live stock due to consumption of poisoned food. Consequently government requirements are very severe and it is necessary to use containers from which powder cannot sift under any circumstances arising during the transportation and handling of containers. It is an object of the present invention to provide a container and closure meeting all of the tests required without unduly complicating the device.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings:—

Figure 1 is a plan view of a container showing the closure fastened in place.

Fig. 2 is a section on line 2—2 of Fig. 1.

Fig. 3 is a plan view of the container, the closure being shown partly inserted.

Fig. 4 is an enlarged section through the interfitting portions of the container and closure.

Fig. 5 is a detail view of one of the handles, its attaching strap being shown in section.

Referring to the figures by characters of reference 1 designates a metal container or drum preferably cylindrical as shown and provided with a head 2 set inwardly from the end of the drum and connected to the drum in the usual or any preferred manner. This head has a central circular opening 3 from the wall of which extends an inwardly projecting circular flange 4. This flange 75 constitutes a portion of the sealing means and also holds the head against buckling.

The closure includes a metal disk 5 having an annular flange 6 the free edge of which is turned laterally and upwardly as indicated at 7 to provide an annular channel 8. The external diameter of flange 6 is approximately the same as the internal diameter of flange 4.

Pivottally mounted on the disk 5 near its periphery are buttons 9 adapted, when in one position, to lie wholly within the circumference of the disk. When the disk is in position in opening 3, however, these buttons can be turned so as to lap head 2 as shown in Fig. 1.

Secured to the disk 5 at diametrically opposed points are straps 10 each having a central transverse arched portion 11 struck therefrom and outstanding from the disk. Projecting into engagement with each of these arched portions are the terminals 12 of loops 13 constituting handles. Said terminals are normally out of alignment as shown particularly in Figure 5 and, as they are held to the disk 5 by the arched portions, the loops 13 will also be held normally against the disk. By swinging the loop away from normal position the terminals 12

will be sprung or forced into alinement, as will be obvious. After the loop has been used as a handle for lifting the closure, it can be swung back against the disk 5 where 5 it will be held until again swung forcibly away from the disk.

After the container has been filled to a point below the flange 4, it can be closed and sealed by inserting the closure edge first 10 downwardly through the opening 3. The closure is capable of slightly buckling to permit this insertion and thereafter said closure is swung to a substantially horizontal position and pulled upwardly by means 15 of handles 13. It might be stated that channel 8 has a soft rubber filling or a filling of any other suitable sealing material indicated generally at 14. Thus when the closure is forced upwardly its flange 6 will 20 frictionally engage and bind tightly upon the inner surface of flange 4 while the inner edge of flange 4 will ultimately become seated in channel 7 and embedded in the sealing material 14. The parts are so nicely 25 proportioned that the closure will be held in place securely by friction only but as a further guarantee against accidental opening of the container the buttons 9 are provided and can be turned into engagement 30 with the head 2.

It will be obvious that the head is reinforced by the container and it is impossible for any pressure exerted from within the container to force the closure from position. 35 This closure and container have withstood

all the requirements of government tests and even when the container becomes battered to almost a shapeless mass it has been possible to remove and replace the closure.

By providing the handles on the closure 40 they not only serve as a means for seating the closure but also provide a means for handling the container and whenever the container is lifted thereby the closure is more firmly forced to its sealing position. 45

By mounting the handles as described they will not swing downwardly to hanging positions and thus tend to drive the closure inwardly should the container be dropped while in an inverted position. 50

What is claimed is:—

The combination with a container having a head opening and a continuous flange extending inwardly from the edge of the opening, of a closure insertible edgewise through the opening and including an annular flange of substantially the same diameter as the opening for frictional engagement with the inner surface of the head flange, an annular channel upon the closure flange, and elastic sealing material in the channel for the reception of the free edge portion of the head flange, a handle upon the closure, and means movably mounted on the closure for engaging the head. 55

In testimony that I claim the foregoing as my own, I have hereto affixed my signature.

JAMES M. COUGHLIN,
